TELEPHONE SYSTEM

Langford J. Bowne, Howard Beach, N. Y., assignor
to Bell Telephone Laboratories, Incorporated,
New York, N. Y., a corporation of New York

Application January 26, 1933, Serial No. 653,592

14 Claims. (Cl. 179—28)

This invention relates to telephone systems and particularly to arrangements for preventing acoustic shocks or high potential signals from penetrating to operator's and subscriber's apparatus.

An object of the invention is to simplify telephone systems in which terminal apparatus is to be protected against acoustic shock caused by high potential signals from external sources or that are transmitted over telephone lines for other signaling purposes, for example, when such telephone lines are used in railway train dispatching systems.

Heretofore, systems have been provided in which telephone lines have been equipped with shock absorbing means to protect terminal equipment from excessive voltages from external sources and yet permit signaling currents of the usual telephone signal voltages to be transmitted over the line to the terminal apparatus. In such systems, vacuum tube circuits were bridged across the line in combination with a filter arrangement whereby when the line was exposed to excessive voltages, such voltages operated the vacuum tube circuit and short-circuited the telephone line and were thus prevented from affecting the terminal apparatus while when ringing signals of ordinary lower telephone voltage were applied to the line, such signals were prevented by filters from operating the vacuum tube circuit and thereby permitted to be transmitted to the terminal apparatus.

One feature of the present invention provides shock protective means for the terminal apparatus against signals of high potential or other excessive voltages from external sources by short-circuiting such signals, while ordinary ringing signals having voltages usual in telephone circuits are permitted to be repeated past said protective means as usual ringing signals to the terminal apparatus.

Another feature of this invention provides means whereby the usual ringing signals may be transmitted from the terminal apparatus out over the line by repeating past the shock protecting means.

Another feature of the invention provides means whereby high potential signals may be transmitted over the telephone line at the call originating end or at any point along the line and whereby such signals are prevented from passing through to the terminal apparatus at the call originating end of the telephone line.

Another feature of the invention provides means at the receiving end of a telephone line or

at any point along the line for translating such high potential signals into low potential ordinary ringing signals to be received by the terminal apparatus at the receiving end of said line or at terminal apparatus at any point along the line, depending on the code represented by the transmitted signals and to protect said terminal apparatus from receiving shocks caused by said high potential signals.

Another feature of this invention provides means whereby an audible tone signal is permitted to pass back over the line as an answer-back signal of the signal received by the selected terminating apparatus.

Another feature resides in the provision of means whereby ordinary low potential ringing signals may be transmitted over the telephone line from a call originating end past the shock absorbing means and whereby signals of the same characteristics may be received at said call originating end incoming over the line and repeated past the shock protecting means at said end.

Referring now to the drawings, Fig. 1 shows in a general diagrammatic form the invention applied to a train despatching system using telephone lines;

Fig. 2 shows the terminating telephone equipment at the calling end of a telephone line and Fig. 3 shows the terminating telephone equipment at the called end of a telephone line used for train despatching and embodying certain features of this invention; and

Fig. 4 shows the terminal equipment at the calling and called ends of a phantom telephone line, the side circuits of which may be used for train despatching embodying certain features of this invention.

Referring now particularly to Fig. 1, the various features have been applied as stated to a train despatching system using telephone lines for the connecting line between terminating stations and way stations comprising a train despatching apparatus. In the particular system illustrated in this figure, 1 represents a so-called despatcher's line while 2 represents a so-called message line.

The message line is ordinarily used only when the despatcher's line is temporarily disabled in which case the message line is by suitable means connected with the terminal apparatus and way stations. The despatcher's line is provided at the calling station A with the train despatcher's telephone set 3 and the usual train despatching calling apparatus 4 represented in diagrammatic form and employed by the train despatcher for selecting way stations. Such systems usually comprise

a key for sending code signals and selectors and suitable circuit arrangements for the transmission of a code signal. At the way stations, such as 5, 6 and 7, the same usual code sending keys and train despatcher's telegraph selector apparatus are provided, while at the receiving station B, equipment similar to that shown at sending station A is provided. If the message line 2 is to be used to call between the stations, it is so arranged that a code calling key equipment is provided at 10 for calling the way stations 11, 12 and 13 or the terminating apparatus at the called station B as shown at 15. The way station apparatus 11, 12 and 13 may be the same as way station apparatus 5, 6 or 7. A terminating station 16, similar to station 15, may also be provided for the establishing of telephone connections between station A and this station 16, or between station B and this station 16. The despatcher's line 1 and the message line 2 may be connected and serve as side circuits of a phantom line circuit terminating at stations A and B in terminal apparatus 18 and 19, respectively. This arrangement is merely shown to illustrate the possibilities of the application of the features of this invention to various types of systems. The various features of this invention are embodied in the terminal apparatus at stations A and B at 18, 10, 19, 15 and 16.

When the message line 2 is used for telephone purposes, the terminal apparatus has to be protected against acoustic shocks caused by the train despatching signals that may affect this line either by the sending of the calling signal from station A to call any of the way stations 11, 12, 13 or 15, or by disturbing influences that may be caused when line 1 is used for train despatching purposes that may be transmitted or effective on line 2 possibly by some disorder due to the connection of the phantom line or any other disturbances. Likewise, the terminal apparatus at 15 and 16 must be arranged to prevent train despatching signals of the same character from affecting the terminal apparatus. The terminal apparatus at 15 is also arranged so that it may be called by train despatching signals transmitted from station A and equipment 10 and these signals are translated into ordinary ringing signals for the calling of the terminal apparatus at this end. Shock absorbing equipment must also be provided at 15 for the prevention of train despatching signals affecting this terminal apparatus. The terminating station 16 is equipped with these protective devices and translating devices the same as station 15. In regard to terminal apparatus 18 and 19, these are arranged for sending and transmitting ordinary ringing signals over the side circuits and if either of the side circuits are used for train despatching signals these terminal apparatus have to be similarly protected from acoustic shock from such signals.

Description will now be made in connection with Figs. 2 to 4 of the various features of this invention relating to the shock protecting devices and the signaling means provided at the terminal apparatus. Figs. 2 and 3 show the terminal apparatus of the message line 2 at stations A and B, respectively. Fig. 3 serves to illustrate both the equipments at 15 and 16 of Fig. 1, while Fig. 2 illustrates the equipment 10 of Fig. 1. Fig. 4 shows the terminal apparatus at 18 and 19 of the phantom circuit of Fig. 1. To illustrate the features of this invention, a description will be made first of a call from the calling station A at 10 over line 2 to call the terminal apparatus

15 at station B and the various functions caused thereby, such as the translation of the train despatching signals into ordinary ringing signals at the terminal apparatus 15 and the ring-back signal caused thereby to be received at the calling station A by the terminal apparatus of line 2. Description will also be made of signaling between terminal apparatus at stations 15 and 16 after said stations have been connected up for telephone purposes. Finally, a description will be made of signaling over the phantom circuit between terminal apparatus 18 and 19. One of these terminal apparatus is represented in Fig. 4 and the description will be made in connection with this figure.

If the call is to be made from the calling station A at 10 over line 2, the calling operator inserts plug 30 into jack 31 and thereby causes the operation of relay 33 over an obvious circuit closed by the jack contacts. This relay, in operating, provides a connection from ground for the middle spring of the train despaching key 34 by means of which the operator may signal out over the next line. The operator may now ring the desired station or terminal apparatus at station B by operating the key 34 to send the desired code. Although only one key has been shown, it should be understood that in ordinary equipment of this type, a number of keys may be supplied, each one having a different code. The operation of this key is such that the connections between the contacts are established on the return of the key to normal when a circuit is completed for the operation of relay 35 from battery through the winding of this relay and lower contacts of key 34 to ground at relay 33. Relay 35 is slow in releasing so that it will remain operated while the code pulses are being sent. With relay 35 operated, a circuit is closed for relays 36 and 37 over obvious circuits. These relays operate to close the circuit from the armature and front contact of relay 35 through the lower armature and front contact of relay 36 and upper armature and front contact of relay 35 to the lead 37' which terminates in the usual special signal apparatus merely shown in diagrammatic form as a box 38. It should be noted that a lead 39 is connected to 38 from the ground at the armature and front contact of relay 33 and key 34 during pulsing. These ground connections on leads 37' and 39 cause the selector apparatus to connect high potential signals to leads 40 in accordance with the code selection on key 34 controlled through the opening and closing of the connection for lead 39 through the two upper contacts of the key.

Referring now to the operation of relays 36 and 37, these relays disconnect the repeating coil 45 from line 2 and connect the repeating coil 46 to the tip and ring conductors in series with the right-hand winding of repeating coil 45. Impulses over leads 40 are transmitted through the left-hand winding of repeating coil 46 to the right-hand winding of this coil and line 2. The protecting means for preventing these high potential low frequency signals from effecting the operator's telephone set 49 during the signaling period comprises a repeating coil 50 having its left-hand windings bridged across the tip and ring conductors towards the operator's telephone set, while the right-hand windings are connected in parallel to the elements of the neon glow tube 51. The impedance of the repeating coil 50 which is normally high to voice frequencies, drops rapidly due to the resistance of the neon lamp breaking down under the high volt-

age signals imposed on it from the repeating coil 50. When the high voltage signal condition is removed, the resistance of the neon tube and impedance of repeating coil 50 return to normal. 5 Because of the rapid functioning of the neon tube 51, practically none of these signaling potentials are impressed upon the repeating coil 45 and electric or acoustic shocks are therefore prevented from affecting the operator's telephone 10 set 49. The repeating coil 45 is also provided to insulate the operator's telephone equipment of the terminal apparatus from normal line currents which may be connected to it by means 15 of the signals transmitted over the line 2 when used as a side circuit for phantom connections illustrated in Fig. 1.

The high potential low frequency code signals incoming at station B to the terminal apparatus at 15 will be received in the usual train despatching signal apparatus shown by means of a box 100. This apparatus is so arranged that the code causes a ground to be applied to the lead 101. Relay 102 is thereby operated over an obvious circuit from battery. This relay connects 25 ringing current through the repeating coil 103, the primary circuit of which is closed from the ringing source 104 through the upper inner armature and front contact of relay 102, while the secondary is connected to the tip and ring conductors at the upper outer and lower outer armatures and front contacts of relay 102. Ringing current is thereby transmitted to operate relay 106 through repeating coil 105. Relay 106 closes a circuit for lighting lamp 107. It should be noted that in this case the train despatching signals do not affect the terminal apparatus as the tip and ring conductors are open at contacts of 30 relay 110. Relay 102 releases at the end of the signaling period as the ground connection on lead 101 is removed when the train despatching signaling apparatus is restored to normal. Audible ringing tone is sent back from this circuit via condensers 111, 112, 113 and 114. This audible answer-back signal is sent back over 35 line 2 to the sending station at A through repeating coil 46, condensers 56 and 57, outer upper armature and front contact of relay 37 and outer lower armature and front contact of relay 36, repeating coil 45, repeating coil 58, jack 31, plug 50 30, to the operator's telephone set 49. The high potential signaling protecting means 50 and 51 do not affect these answer-back signals to any appreciable extent.

To answer this call, the operator will, on seeing 55 the lamp 107 lighted, insert a plug 115 in the jack 116 and thereby close the circuit through the sleeve terminals for the operation of relay 110. This relay now connects the tip and ring conductors through for talking. In case any disturbing high voltage signals are received over 60 the line while this connection exists, such as, for example, might happen in case of signaling from a way station by train despatching signals, the operator's telephone set 118 if connected at this 65 time will be protected from acoustic shocks by the protecting means comprising a repeating coil 120 having its right-hand windings bridged across the tip and ring conductors and its left-hand windings connected to the neon tube 122. This 70 arrangement of repeating coil 120 and tube 122 operates in the same manner as described in connection with the terminal apparatus at station A, namely, to short-circuit the high potential low frequency code signals.

75 The terminal apparatus 15 is provided for re-

ceiving and sending low potential ringing signals. Such signals will be received or transmitted under circumstances such as, for example, when the terminal apparatus 15 has been called and connected up to an operator's position and where 5 the terminal apparatus 16, for example, has also been called and connected up to an operator's position. If, under these circumstances, for example, the operator at 118 desires to call the operator connected to the terminal apparatus at 10 16, he will operate his usual ringing key 123 and thereby cause the operation of the ringing relay 124. This relay, in turn, closes a circuit for the operation of ringing relay 125 at its inner right-hand armature and front contact and short-circuits the line at its right-hand armature and front contact to prevent relay 131 from operating falsely. Relay 125, in operating, closes an obvious circuit for the operation of relay 126. This relay opens the circuit for relay 110 which releases and connects the tip and ring conductors of line 2 through the contacts of relay 126, to the ringing current source 104 through the windings of repeating coil 103. Relay 126 also closes a circuit for the operation of relay 129. When 20 25 the ringing current from the operator's cord ceases, relays 124, 125 and 126 are released and relay 110 reoperates. At this time a surge of current from the line may cause relay 131 to operate falsely due to the connection established 30 by the reoperation of relay 110. Relay 129 which is slow in releasing will hold over between the time of the release of relay 126 and the operation of relay 131 if it should operate due to such line circuit, so that relay 129 will be held operated 35 from the contacts of relay 131 until line current surges are dissipated. Relay 129 opens the circuit from the contact of relay 131 to the winding of relay 102, thus preventing a false ringing signal being sent back to the operator. 40

If the operator at 118 is to be called by a re-ringing signal from, for example, the terminal equipment 16, the signal current is transmitted over the line and is received by the operator at 118. This signal causes the operation of relay 45 131 and the operation of this relay closes an obvious circuit for the operation of relay 102 which connects ringing current to the operator at 118 in the same manner as when this relay operated due to a train despatching signal as hereinbefore 50 described.

Referring now to Fig. 4, description will be made of this circuit when used as the terminating apparatus at 18, for example. In this case if the operator at 200 inserts her plug 201 into 55 the jack 203 and operates her ringing key 204, relay 205 operates. This latter relay short-circuits the tip and ring conductors outgoing over the phantom circuit by its outer left-hand armature and front contact and closes a circuit for 60 the operation of relay 207. Relay 207 closes an obvious circuit for the operation of relay 208 to connect the right-hand winding of the repeating coil 209 to the tip and ring conductors outgoing over the phantom circuit and to connect 65 the left-hand winding of the repeating coil to the ringing current source at 210. Ringing current will now be transmitted out over the phantom circuit to call the terminal apparatus at 19. Relay 208, in operating, also closes an obvious 70 circuit for relay 211 for the same purpose as relay 129 was operated in terminal apparatus 15, namely, to prevent surges from the line from affecting the operator's set due to the possible false operation of relay 212. If this terminal 75

apparatus is called over the phantom circuit, relay 212 is operated thereby causing the operation of relay 214 which relay, in turn, closes connections for the transmission of ringing current 5 from source 210 and its upper and lower outer armatures and front contacts through repeating coils 209 and 216 for the operation of ringing relay 217 which, in operating, lights lamp 218.

10 This terminal apparatus is protected from the high voltage low frequency signals incoming over the phantom circuit due to train despaching signals over either the message line or the despaching line by the same type of means as the 15 terminal apparatus at 10 or 15, namely, repeating coil 220 and neon glow lamp 221. It is seen by the location of the repeating coils across the tip and ring conductors in this circuit that it is necessary to relay both incoming and outgoing 20 ringing signals past the equipment.

What is claimed is:

1. In a signaling system, an exchange, a line connected to said exchange, means for transmitting high potential low frequency current signals out over said line, protective means for preventing said signals from passing towards the exchange, means for connecting said protective means in the line during the transmission of said signals, and means for receiving low potential 25 high frequency signals at said exchange incoming over said line while signaling with high potential low frequency current.

2. In a signaling system, an exchange, a line incoming to said exchange, a high potential current source, signaling means including a key for producing low frequency alternating current signals from said high potential current source, a repeating coil for coupling said signaling means to said line for the transmission of high potential low frequency alternating current signals out over said line when said key is operated, protective means including a repeating coil and a neon glow tube for preventing said high potential low frequency alternating current signal from 40 passing towards the exchange, and means including said first mentioned coupling repeating coil for receiving low potential high frequency signals at said exchange incoming over said line while signaling with the high potential low frequency alternating current.

3. In a telephone system, an operator's telephone set, a line, means for connecting said telephone set to said line, means for transmitting high potential low frequency alternating current signals out over said line, means for preventing said signals from passing to said telephone set, means for connecting said last mentioned means in said line during the transmission of said signals, and means for transmitting low potential 55 high frequency signals to said telephone set received over said line while high potential low frequency alternating current signals are transmitted out over said line.

4. In a telephone system, an operator's telephone set, a line, means for connecting said line to said operator's telephone set, means operative in response to the establishing of said connection for transmitting high potential low frequency alternating current signals out over said line and for preventing said signals from acoustically affecting said telephone set, and means for acoustically detecting in said telephone set low potential high frequency signals received 70 over said line while signaling with said high po-

tential low frequency alternating current signals.

5. In a signaling system, a line, means responsive to high potential low frequency signals received from one end of the line for converting said signals into low potential signals for transmission out over both ends of the line, means for repeating low potential signals over said line from either end thereof, and means for preventing high potential signals incoming from said one 10 end of the line from penetrating to the other end of the line.

6. A transmission line, a protective device associated with said line for short-circuiting high potential signals incoming over said line, a relay 15 on each side of said protective device responsive to low potential signals on said line, and means responsive to the operation of either relay for transmitting low potential signals out over the opposite end of the line past said protective device.

7. In a signaling system, an exchange, a line incoming to said exchange, means responsive to high potential low frequency alternating current signals received over the line for converting said 25 signals into low potential ringing frequency signals for transmission to the exchange, means for signaling out over the line with low potential ringing frequency signals in response to the reception of said high potential low frequency alternating current signals incoming over the line, means for repeating low potential ringing frequency signals over said line from either end thereof, and means for preventing high potential low frequency signals incoming over the line from 30 passing over said line towards the exchange.

8. In a telephone system, an operator's position including an operator's telephone set, a line incoming to said position, means associated with said line responsive to high potential low frequency alternating current signals received over the line for transmitting low potential ringing frequency signals to said position, means for repeating said low potential ringing frequency signals out over the line, means for repeating low potential ringing frequency signals incoming over said line to said position, means for repeating low potential ringing frequency signals from said position out over said line, and means for preventing incoming high potential low frequency signals 40 incoming over the line from causing acoustic 45 shocks in said telephone set.

9. In a telephone system, a first and a second exchange, an operator's position including a telephone set at said second exchange, a line interconnecting said exchanges, means for connecting said line to said position, means at said first exchange for signaling over said line with high potential signals, means at said second exchange for translating said high potential signals into low potential signals for transmission to said position, an acoustic shock absorbing means at said second exchange for preventing transmitted high potential signals from penetrating to said position to affect the operator's telephone set, and means for repeating low potential signals received over said line in either direction past said acoustic shock absorbing means.

10. In a telephone system, an operator's cord circuit including an operator's telephone set, a line, means for connecting said line to said cord circuit, acoustic shock absorbing means in said line for preventing high potential low frequency signals incoming over the line from affecting said operator's telephone set, means responsive to high 70 75 80 85 90 95

potential low frequency alternating current signals received over the line for converting said signals into low potential ringing frequency signals for transmission past said acoustic shock absorbing means to said operator's cord circuit, and means for repeating low potential ringing frequency signals past said acoustic shock absorbing means when said signals are received from the line to the operator's cord circuit or when they are received from said operator's cord circuit to the line.

11. In a signaling system, an exchange, a line incoming to said exchange, a high potential low frequency alternating current signal receiving means associated with said line, an acoustic shock absorbing means associated with said line, means for converting high potential low frequency signals received by said means into low potential ringing signals and for transmitting said low potential ringing signals past said acoustic shock absorbing means towards said exchange, and means responsive to said low potential ringing signal for transmitting audible tone over said line past said acoustic shock absorbing means out over said line away from said exchange.

12. A transmission line, a protective device associated therewith for short-circuiting high potential signals incoming over said line, a relay associated with said line responsive to low potential alternating current signals of a higher frequency, and means responsive to the operation of said relay for transmitting signals over said line past said protective device.

13. In a signaling system, a calling station, a called station, a line connecting said stations, high potential current code signal transmitting means at said calling station for transmitting code signals over the line to call any one of said called stations, means at the calling station for preventing said code signal from passing back beyond said calling station, means at each of said called stations for responding to a particular code signal transmitted over the line and for translating said code signal into a low potential ringing signal for transmission beyond said called station and for transmission back over the line 10 towards the calling station, means at the called stations for preventing any code signals transmitted over the line from passing beyond the called stations, means at the calling station for transmitting a low potential signal received over 15 the line from a called station back beyond said calling station, means at a called station operative if said called station has not been previously called by a code signal for transmitting low potential signals back over said line, and 20 means at any called station operative if previously called by a code signal for transmitting low potential signals incoming over the line beyond said called station.

14. In a signaling system, a line, means for transmitting low potential ringing signals to both ends of said line, means for repeating said low potential ringing signals over said line incoming from either end, means for transmitting high potential signals from one end of said line, means 30 for preventing said high potential signals from passing through to the other end of said line, and means responsive to said high potential signals for transmitting low potential signals to said other end of said line.

35 LANGFORD J. BOWNE.
